(57) **CLAIM**

The ornamental design for a vaporizer assembly, as shown
and described.

DESCRIPTION

FIG. 1 is a top plan view of a first embodiment of the
vaporizer assembly showing my new design;

FIG. 2 is a top perspective view of thereof;

FIG. 3 is a side elevational view thereof, wherein the views
from all sides are identical;

FIG. 4 is a top plan view of a second embodiment of the
vaporizer assembly, wherein the second embodiment has an
opaque rather than transparent container portion;

FIG. 5 is a top perspective view of the second embodiment
of the vaporizer assembly; and,

FIG. 6 is a side elevational view of the second embodiment
of the vaporizer assembly, wherein the views from all sides
are identical.

A broken line showing is for illustrative purposes only and
forms no part of the claimed design.
